Frank Skupien, 5443 S. Wolcott St.,
Chicago, Ill. 60609

Filed Nov. 3, 1966, Ser. No. 4,576

Term of patent 14 years

(Cl. D44—9)

FIGURE 1 is a perspective view of one side of a combined tumbler and saving bank, showing my new design, with the cover thereof shown in detached position;

The essential features of the design are shown in full lines.

I claim:

The ornamental design for a combined tumbler and saving bank, substantially as shown and described.
